COMBINED DOLL AND VEHICLE

Guy J. Colwell, Hollywood, Christie M. Matson, Los Angeles, and C. Gordon Shireman, Rolling Hills Estates, Calif., assignors to Mattel, Inc., a corporation of California

Filed Nov. 16, 1967, Ser. No. 9,441

Term of patent 14 years

(Cl. D34—15)

The dominant features of our design reside in the full line portions shown.

We claim:

The ornamental design for a combined doll and vehicle, as shown and described.
